DESIGN FOR A COMBINED SWITCH CASING AND HANDLE

Carl W. Sundberg and Montgomery Ferar, Detroit, Mich., assignors to Bulldog Electric Products Company, Detroit, Mich.

Application January 20, 1936, Serial No. 60,683

Term of patent 14 years

To all whom it may concern:

Be it known that we, Carl W. Sundberg and Montgomery Ferar, citizens of the United States and residents of Detroit, Michigan, have invented a new, original, and ornamental Design for a Combined Switch Casing and Handle, of which the following is a specification, reference being had therein to the accompanying drawing.

In the drawing,

Fig. 1 is a front view of the combined switch casing and handle showing our new design;

Fig. 2 is a side view as if from the right of Fig. 1.
We claim:

The ornamental design for a combined switch casing and handle, substantially as shown.
In testimony whereof we affix our signatures:

CARL W. SUNDBERG.
MONTGOMERY FERAR.
